LAPPING MACHINE

Herbert S. Indge, Westboro, Mass., assignor to
 Norton Company, Worcester, Mass., a corpora-
 tion of Massachusetts

Application February 14, 1940, Serial No. 318,789

3 Claims. (Cl. 51—117)

The invention relates to lapping machines, and more particularly to an opposed wheel lapping machine for simultaneously lapping the opposed faces of a work piece.

One object of the invention is to provide a simple and thoroughly practical lapping machine. A further object of the invention is to provide an improved driving mechanism for the lower lapping element and work carrying cage. Another object of the invention is to provide the improved lap and cage driving mechanism with means to prevent dust and grit from getting into the mechanism. A further object of the invention is to provide adequate dust and lubricant seals to prevent the admission of dust and grit to the driving mechanism. A further object of the invention is to provide a self-contained lubricant system whereby the chamber surrounding the cage driving mechanism is maintained full of lubricant under pressure. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of the various possible embodiments of the mechanical features of this invention,

Fig. 1 is a side elevation of the improved lapping machine, having parts broken away to more clearly show the construction; and

Fig. 2 is a fragmentary sectional view on an enlarged scale, taken approximately on the line 2—2 of Fig. 1.

Referring more particularly to the embodiment illustrated, the lapping machine may be 40 constructed in its general aspects similar to the lapping machine illustrated in my prior U. S. Patent No. 2,103,984 dated December 28, 1937. This machine, as illustrated, may comprise a base 10 which rotatably supports a lower lapping 45 wheel 11. The base 10 is provided with an upwardly extending column 12 having an outwardly extending horizontal portion 13 which rotatably supports a vertical spindle 14. The spindle 14 carries a rotatable lapping wheel 15 which is connected to the lower end of the rotatable spindle 14 by means of a supporting plate 16.

Power may be obtained from any suitable source, such as an overhead drive shaft or an electric motor mounted on the machine. For

the sake of illustration, a belt drive has been shown comprising a driving belt 20 which serves to rotate a pulley 21. The inner portion of the pulley 21 is formed as one part of a cone clutch.

5 A slidably mounted cone clutch member 22 serves to mate with the clutch face within the pulley 21 to transmit a rotary motion to a rotatably mounted drive shaft 23 which is journaled in suitable bearings 24, 25, 26 and 27 in the base 10. The clutch member 22 is slidably keyed to the shaft 23. When the clutch member 22 is in the full line position (Fig. 1), no power is transmitted to the shaft 23. When it is desired to rotate the shaft 23, the cone clutch member 22 is moved toward the right (Fig. 1) into engagement with the cone clutch member within the pulley 21 so as to cause rotation of the shaft 23.

In order that the clutch may be readily actuated from an operating position adjacent to the front of the machine, a pivotally mounted control lever 28 is supported on a stud 29 on the base 10 of the machine. The lower end of the lever 28 is connected by a stud 30 with a link 31. The link 31 is in turn connected by a stud 32 with the forward end of a slidably mounted rod 33. The rod 33 is journaled in bearings 34 and 35 which are fixedly mounted on the base 10 of the machine. The rod 33 supports a vertically extending arm 36 which is yoke-shaped at its upper end and engages a groove 37 formed integral with the clutch member 22. By movement of the control lever 28 in a counterclockwise direction (Fig. 1), the clutch member 22 may be thrown into engagement with the clutch member formed within the pulley 21 to cause rotation of the shaft 23. An arrow point 37a projecting from the yoked portion of the arm 36 cooperates with a spring-pressed plunger 38 to maintain the clutch member 22 either in or out of engagement with the clutch member formed within the pulley 21. Similarly, when the lever 28 is moved in a clockwise direction into the position illustrated in Fig. 1, the clutch member 22 is disengaged, thus stopping the rotation of the shaft 23 so as to stop not only the rotation of the lower lapping wheel 11 and the upper lapping wheel 15 but also a work supporting cage to be hereinafter described.

50 The shaft 23 is also provided with a worm 40 which meshes with a worm gear 41 mounted on the lower end of a vertical rotatably mounted shaft 42. The shaft 42 is connected by a universal joint 43 with the lower end of a shaft 44. The shaft 44 is preferably a telescopic shaft and is

connected at its upper end by a universal joint 45 with the lower end of a rotatable shaft 46 which is supported in suitable bearings, not shown, in a bracket 48 which is adjustably mounted on top of the column 12. The shaft 46 is provided with a multiple V-groove pulley 50 which is connected by multiple V-belts 51 with a multiple V-groove pulley 52 slidably keyed to rotate the vertical spindle 14. When the clutch member 22 is thrown into engagement, a rotary motion is transmitted through the mechanism above described to rotate the pulley 50 which transmits a rotary motion through the V-belts 51 to the pulley 52 to rotate the vertical spindle 14 and thereby rotate the upper lapping wheel 15 as desired.

The lower lapping wheel 11 is connected by a rotatable spider 55 to the upper end of a vertically arranged rotatable sleeve 56. The spider 55 is keyed by means of a key 57 so as to rotate with the sleeve 56 in a manner to be hereinafter described. The sleeve 56 is journaled in bearings 58 and 59 which are carried by a frame 60 which is fixedly bolted to the base 10 of the machine. A worm gear 61 is keyed to the lower end of the sleeve 56 and meshes with a worm 62 mounted on the drive shaft 23. When the drive shaft 23 is rotated, a rotary motion is transmitted through the worm 62 and the worm gear 61 to rotate the sleeve 56 and thereby rotate the spider 55 and the lower lapping wheel 11.

The sleeve 56 also supports a gear 63 which meshes with a gear 64 mounted adjacent to the lower end of a rotatable shaft 65. The shaft 65 also carries a small gear or pinion 66 at its lower end which meshes with a gear 67 which is keyed to the lower end of a rotatable shaft 68. The shaft 68 is rotatably supported in suitable bearings 69 and 70 which are supported within the sleeve 56. The shaft 68 serves as a driving means for a work supporting cage 12 which is provided with a plurality of work receiving apertures to simultaneously support a plurality of work pieces 73 for a lapping operation between the opposed rotatable lapping wheels 11 and 15. A head 75 is keyed to the upper end of the shaft 68 so as to rotate therewith. The head 75 serves as a support for a plurality of studs 76, preferably three symmetrically arranged studs, only one of which is illustrated in Fig. 2. These studs 76 are equally spaced from each other and are equidistant from the spindle 68 about which they revolve. Upon each one of the three studs 76 is rotatably mounted a gear 77. The gears 77 are arranged to continuously mesh with an internal ring gear 78 which is fixedly mounted within the spider member 55. A gear 79 is formed integral with or fixedly mounted relative to each of the gears 77. The gears 79 are arranged to continuously mesh with a gear 80 which is rotatably supported by an anti-friction bearing 81 on the upper end of the shaft 68.

Three other studs 82 (only one of which has been illustrated in Fig. 2) are fixedly supported by the head 75 equi-distant from each other and also equi-distant from the shaft 68 about which they revolve. A gear 83 is rotatably mounted on each of the studs 82 in such a position as to be continuously in mesh with a pinion 84 which is either formed integral with or fixedly mounted to rotate with the gear 80.

A casing 85 is formed as an integral part of the spider 55 and serves as a casing or container which surrounds the gear cage driving mechanism and serves as a lubricant container in which

the gears rotate. A cover plate 86 encloses the upper open end of the casing 85. A pair of dust and lubricant packing rings 87 and 88 are provided to prevent lubricant leaking from the casing 85 and also to prevent dust from entering within said casing and thus coming in contact with the moving parts. A cap 89 is fastened by screws 91 to the hub of each of the three gears 83 so that it will rotate concentric therewith. Each of the caps 89 serves as a support for a work cage supporting and driving pin 92. The driving pin 92 may be fixedly mounted relative to the cap 89 or may be adjusted relative thereto to vary the amount of motion transmitted thereby to the cage 72. Each of the caps 89 is provided with dust and lubricant packing rings 94. Also, packing rings 95 are interposed between the cover plate 86 and the cap 89, thus forming a double seal against lubricant leakage from the casing 85 or grit passing through into the gear mechanism contained within the casing 85.

When the shaft 23 is rotated, the worm 62 will transmit a rotary motion through the worm gear 61 to rotate the sleeve 56 and spider 55 to rotate the lower lapping wheel 11. At the same time, the rotation of the sleeve 56 transmits a rotary motion through the gear 63, the gear 64, the gear 66, the gear 67, to rotate the shaft 68. Rotation of the shaft 68 serves to rotate the head 75 which in turn transmits a rotary motion through the spaced cage driving pins 92 to rotate the cage 12 during a lapping operation. The gears 77 rolling in mesh with the stationary ring gear 78 transmit a rotary motion through the gears 79 to the central gear 80 and pinion 84 which in turn transmits a rotary motion to the three gears 83 which simultaneously rotate the caps 89. The cage driving pins 92 are usually arranged off center relative to the axis of rotation of the caps 89. Therefore, any rotary motion of the caps 89 causes a gyrating movement to be imparted to the cage member 72 during the rotation thereof, thus providing a combined rotary and gyrating movement of the work carrying cage 12 simultaneously to move a plurality of work pieces 73 through an irregular path between the operative faces of the lapping wheels 11 and 15 simultaneously to lap the opposed faces thereof.

In order to attain one object of the invention, it is desirable to provide a lubricant system whereby the chamber within the casing 85 may at all times be maintained filled with lubricant under pressure so as to prevent the formation of a partial vacuum with the resultant sucking in of grit and other foreign material which would rapidly wear the cage driving parts and bearings therefor. In the preferred form, a self-contained lubricant system is provided comprising a lubricant reservoir 99 formed within the base 10 of the machine. A lubricant pump 100 is formed integral with a cover plate 101 for convenience of assembly. The lubricant pump 100 comprises a reciprocable plunger 102 which supports a roller 103 on a stud 104 which is carried by a bracket 105 fixedly mounted on the end of the plunger 102. An eccentric 106 is mounted on the drive shaft 23 and serves through the roller 103 to transmit a reciprocatory movement to the pump plunger 102 when the shaft 23 is rotated. A compression spring 107 serves at all times to maintain the roller 103 in operative engagement with the cam or eccentric 106.

Lubricant under pressure is pumped from the

reservoir 99 through a strainer 108, through a pipe 109, through a ball check valve 110, into a pump chamber 111. When the plunger 102 reciprocates, fluid is forced under pressure through a ball check valve 112 and through a passage 113 and a pipe 114 to a central aperture 115 within the spindle or shaft 68. Lubricant under pressure is forced through the aperture 115, which extends through the entire length of the spindle 68, into the chamber 116 within the casing 85 to entirely fill the chamber 116 formed by the casing 85 and the integral spider 55. It will thus be seen that the gear mechanism for driving the work carrying cage 72 through an irregular combined rotary and gyrating movement is entirely surrounded by lubricant under pressure so that all of the moving parts are adequately lubricated. It is desirable to maintain a sufficient pressure on the lubricant within the chamber 116 to prevent any air pockets or creation of a partial vacuum, so as to prevent dust or foreign matter from working into the chamber 116 by passing the oil and grit seals above described.

In order to maintain a uniform pressure on the lubricant within the chamber 116, an adjustable ball check valve 117 is provided. Lubricant under pressure within the chamber 116 fills a vertically extending passage 118 to the ball check valve 117. The ball check valve 117 is maintained in a closed position by means of a spring 119, the tension of which may be adjusted by means of a screw 120. By varying the tension of the spring 119, the pressure of the lubricant within the chamber 116 may be varied as desired. When the pump 100 forces lubricant into the chamber 116 to the extent that the pressure rises above the pressure set for the ball check valve 117, the ball 117 is forced downwardly to allow excess lubricant under pressure to pass through a passage 121 formed in the casing 85. Lubricant passing through the passage 121 may pass downwardly through an enlarged bore or chamber 122 within the bracket 60 and drains through a passage 123 into the reservoir 99 within the base 10. By adjustment of the screw 120, the pressure of the lubricant within the chamber 116 may be readily varied as desired, so that it is sufficient to maintain a full chamber of lubricant and sufficient to prevent creation of a partial vacuum and thus stop leakage of grit or foreign matter by the lubricant and dust seal rings 87 and 88. In case the passage 118 should become clogged, a second ball check valve 125 is provided which is connected by a short passage with the lower portion of the chamber 116. A screw 126 is provided for adjusting the compression of the spring 121. This ball check valve 125 is adjusted to a slightly higher pressure than the ball check valve 117 so that normally the ball check valve 117 functions to release excess lubricant under pressure. In case of a stoppage in the passage 118 and a resultant increase in lubricant pressure within the chamber 116, the ball check valve 125 will open and allow lubricant from the lower portion of the chamber 116 to pass outwardly through the ball check valve 117 and thereby return to the reservoir 99.

The operation of the improved lapping machine will be readily apparent from the foregoing disclosure. The reservoir 99 within the base 10 is filled with lubricant sufficient to maintain a level substantially up to the center of the

drive shaft 23, thus providing adequate lubrication for the gear mechanism within the base. When a lapping operation is started and the control lever is shifted to engage the clutch member 22 to start a rotary motion of the shaft 23, the rotation of the eccentric 106 starts reciprocation of the pump plunger 102 to force lubricant through the central aperture 115 in the shaft 68 to maintain a desired and predetermined lubricant under pressure filling the entire chamber 116 within the casing 85 to adequately lubricate the gears and bearing parts, maintaining a full chamber and thus preventing creation of a partial vacuum and eliminating the danger of dust, grit or foreign material passing the lubricant and dust seals, as above enumerated.

It will thus be seen that there has been provided by this invention apparatus in which the various objects hereinabove set forth together with many thoroughly practical advantages are successfully achieved. As many possible embodiments may be made of the above invention and as many changes may be made in the embodiment above set forth, it is to be understood that all matter hereinbefore set forth or shown in the accompanying drawings is to be interpreted as illustrative and not in a limiting sense.

I claim:

1. In a lapping machine having a base, a work carrying cage, means including a gear mechanism to rotate and gyrate said cage, a rotatable casing surrounding said mechanism, a lubricant pump within the base, lubricant connections between said pump and said casing, means to actuate said pump to maintain lubricant under pressure within said casing, and means including an adjustable relief valve in said casing whereby the lubricant pressure may be varied as desired.
2. In a lapping machine having a base, a rotatable lapping wheel, a work carrying cage, a hollow casing to support said wheel, means including a gear mechanism within said casing to rotate and gyrate said cage, means including a rotatable drive shaft in the base which is operatively connected to rotate said lapping wheel and to actuate said gear mechanism, and a lubricant system within said base including a lubricant reservoir, a lubricant pump, lubricant connections between said pump and casing, driving connections between said shaft and pump, and an adjustable relief valve in said casing whereby said casing may be maintained filled with lubricant under a desired and predetermined pressure.
3. In a lapping machine having a base, a rotatable lapping wheel, a work carrying cage, a hollow casing to support said wheel, means including a gear mechanism within said casing to rotate and gyrate said cage, means including a rotatable drive shaft in the base which is operatively connected to rotate said lapping wheel and to actuate said gear mechanism, and a lubricant system within said base including a lubricant reservoir, a lubricant pump, lubricant connections between said pump and said casing, an adjustable pressure relief valve in said casing, and an eccentric on said drive shaft to actuate said pump whereby lubricant under the desired and predetermined pressure may be maintained in said casing.

HERBERT S. INDGE.
